UNITED STATES PATENT OFFICE.

JOSEPH P. HULDER, OF NEW YORK, N. Y., ASSIGNOR TO THE UNIT PLAYER ACTION CO., A CORPORATION OF NEW YORK.

TRACKING DEVICE FOR PLAYER PIANOS.

1,422,713.

Specification of Letters Patent. Patented July 11, 1922.

Application filed October 19, 1920. Serial No. 417,893.

To all whom it may concern:

Be it known that I, JOSEPH P. HULDER, a citizen of the United States, and a resident of the city of New York, in the county of Bronx and State of New York, have invented certain new and useful Improvements in Tracking Devices for Player Pianos, of which the following is a specification.

This invention relates to improvements in tracking devices for player pianos or other musical instruments employing traveling perforated note-sheets, of the type in which correct registration between the perforations in the sheet and the corresponding openings in the tracker-bar is automatically maintained by means of pneumatic apparatus, the operation of which is governed by a guide-opening over which an edge of the sheet travels.

In a pneumatic tracking device of this type, it is necessary to provide a bleed at some point between the air exhausting apparatus and the guide-opening passage so that said passage will be under exhaust while the sheet is tracking properly. It has been found in practise that the bleeds frequently become clogged with particles of dust or lint which are drawn in through the guide-opening, and thereby hamper or prevent proper operation of the device. Slight lateral displacements of the note-sheet, particularly in the case of the modern note players, are sufficient to disturb the alignment of the perforations and the openings in the tracker-bar. Now as the area of the bleed is necessarily small, and as the device should be responsive to slight displacements of the sheet, it will be readily seen that even a partial clogging of the bleed impairs efficient working. Furthermore, in such mechanisms, as now constructed, the bleeds are relatively inaccessible and in order to clean the same they must, generally, be removed.

One of the objects of my invention is to overcome these defects by provision of a groove formed in the face of the tracker-bar or an appurtenant part thereof, which groove, when covered by the traveling note-sheet, constitutes the "bleed," and is practically self-cleaning inasmuch as any dust or

lint that is lodged in the groove will be drawn out by the suction or draft created by re-rolling the sheet.

Another object is to mount all of the operative parts of the tracking device on a carriage which is movable longitudinally with relation to the tracker-bar, and whereby transposition of the note-sheet may be effected without interference with the operation of said device.

A further object is to provide pneumatic means for automatically centering the note-sheet carrying roll, so as to assure that the sheet will re-wind properly and that it will pass over the groove, whereby to clean the latter, during re-rolling.

To these ends, as well as others not specifically mentioned, my invention consists in certain novel features of construction, arrangement and combination of parts, herein-after described and particularly pointed out in the claims.

In the accompanying drawings, illustrating a preferred form of my invention;

Figure 1, is a front view of a combined transposing and automatic tracking device embodying the invention;

Fig. 2, is a detailed view, partly in section, showing portions of the carriage and the operative parts of the tracking device mounted thereon; and,

Fig. 3, is a horizontal section on the line 3—3 of Fig. 1.

The tracker box is fixed to a suitable part of the instrument (not shown) and consists of a pair of side walls 1 and 2, and a rear wall 3. A tracker-bar 4, having the usual openings 5, extends across the front of the tracker box. A bracket 6, carried on a pair of rods 7—7, is provided to support the mechanism for driving the note-sheet 13. As such mechanisms are well known in the art, I have, for the sake of clarity, merely indicated the driving mechanism on the drawings.

One feature of my invention resides in the provision of a carriage which is movable longitudinally, in either direction, with respect to the tracker-box, and upon which the operative parts of the tracking device are mounted. This carriage comprises end members 8 and 9, and longitudinally extending

rods 10 and 11 which pass through and are supported in openings in the side walls of the tracker-box.

The carrying roll 12, which carries the perforated note-sheet 13, is supported at one end on a thrust bearing 14 and at its other end on a longitudinally movable spindle 16. The bearing 14 is carried in a sleeve 15 which projects inwardly from the end member 8 of the carriage. The take-up roll 17 is loosely mounted on a spindle 18 and is driven by means of a pin 19 projecting from a collar 20 keyed to the spindle and engaging an opening in the flange of said roll.

15 A screw 21 threadedly engages a nut 22 secured to the end 8 of the carriage. The shank of the screw is supported in a bracket 23 bolted to the tracker box wall 1. The screw has a knurled head 24 whereby it can 20 be turned. A collar 25, fastened to the inner end of the shank, prevents endwise movement of the screw with respect to the support 23. 25 26 is an arm depending from the carriage member 8 and carrying at its lower end a bent arm 27 which engages in a circular groove 28 formed in the hub 29 of the take-up roll 17. An adjusting screw 30 is provided to limit the travel of the carriage. It will be seen from the foregoing description 30 that by merely turning the screw 21, the carriage together with the parts mounted thereon may be moved to the right or left, as the case may be, and thereby effect transposition of the note-sheet.

35 31 is a power pneumatic of known construction secured to the outer face of a valve box 32, which valve box is mounted on the end member 8 of the carriage. An arm 33 is carried by the movable member of the 40 pneumatic 31 and is connected by a rod 34 with a lever 35, which lever is fulcrumed at 36 in a right angled support 37 fixed to the end member 9 of the carriage. The end of the rod 34 which engages the lever 35 is 45 threaded and provided with lock nuts 38 to permit of adjustment. The lever 35, at a point intermediate its ends, abuts against the outer end of the spindle 16. In operation of the tracking device, when the pneumatic 31 collapses, the lever 35 will be drawn to the 50 left, thus shifting the spindle 16 and the note-sheet carrying roll 12 in that direction. When, on the other hand, the pneumatic 31 expands, the thrust bearing 14 will force the 55 roll 12 and spindle 16 in the opposite direction. It will be understood that only a slight shifting of the sheet in one direction or the other is required to correct improper tracking.

60 The tracker-bar 4 is notched at 39 to receive a plate 40 which is fastened to the rod 10 of the carriage, preferably by means of a sleeve 41 and screw 42 so as to permit of adjustment. 43 is a guide fastened to the plate

40 and received in a longitudinal groove 44 65 formed in the lower edge of the tracker-bar adjacent to the ends of the notch 39. The face of the plate 40 is flush with that of the tracker-bar so that the note-sheet can travel smoothly over it, and the notch 39 is wider 70 than the plate to permit of longitudinal adjustment of the latter. It will be seen that the plate 40 will move with the carriage when the latter is shifted to effect transposition of the note-sheet. To facilitate transposition, the tracker-bar is preferably provided with graduations above the notched portion 75 39 and the plate 40 with an index mark, as seen in Fig. 2.

The means for governing or inaugurating 80 operation of the tracking device include two openings 45 and 46, and a connecting groove or channel 47. Preferably these openings and groove are formed in the face of the adjustable plate 40 of the tracker-bar, but it 85 is to be understood that I do not limit myself in this respect as I am aware that the openings and groove may be formed in the face of the tracker-bar itself, or in the face of some other appurtenant part. 90

The opening 45 constitutes the "guide-opening" and it is so positioned or adjusted as to be partly covered by an edge of the note-sheet 13, as indicated by the dotted line in Fig. 1, when said sheet is traveling 95 properly. The opening 46, which communicates with the air exhausting apparatus of the instrument and which may be called the "exhaust-opening," is disposed so as to be entirely covered by the edge portion of the 100 traveling sheet. The groove 47, which connects the "guide-opening" 45 and the "exhaust-opening" 46, is formed with a cross-sectional area which is substantially equal to the area of the normally uncovered portion of the "guide-opening" 45. This groove, when covered by the traveling note-sheet, constitutes the "bleed" between the "guide-opening" and the "exhaust-opening." Now, as the area of the "bleed" is substantially 105 equal to that of the normally uncovered portion of the "guide-opening," it is evident that the air which enters said opening while the note-sheet is tracking properly will be exhausted through the "bleed," and that the 110 pneumatic tracking device will accordingly remain inactive. When, however, lateral displacements of the sheet occur, either more or less of the "guide-opening" will be covered and will thereby inaugurate operation of the tracking device to automatically 115 correct the displacement. 120

The "guide-opening" 45 is connected through a tube 48 with the chamber 49 under the diaphragm 50 of an ordinary pneumatic 125 puppet valve 51, which valve communicates with the power pneumatic 31 through the passage 52. In tracking devices of the type

to which this invention relates it has been usual to couple the "guide-opening" directly with the pneumatic without intervention of a controlling valve. By means of my improvement, whereby I provide a pneumatic valve for controlling operation of the pneumatic 31, I am enabled to produce a tracking device which is much more sensitive, and which re-acts with greater rapidity, to correct displacements of the note-sheet than do those of the prior art which operate by admission of air directly to the pneumatic.

The "exhaust-opening" 46 communicates through a tube 53 with an exhaust chest indicated at 54, which chest forms a part of the usual air exhausting apparatus employed in such instruments. A tube 55 connects said chest with the valve 51, and a branch tube 56 connects the chest with a port 57 opening 20 into the pneumatic 58 next described.

The principal function of the pneumatic 58 is to centralize the roll 12 during re-rolling of the note-sheet 13 so as to assure that the sheet will be properly wound up and that an edge of the sheet will pass over the groove 47 while the sheet is being re-rolled. This pneumatic is fastened to and carried on the outer face of the movable member of the power pneumatic 31, with the hinged end of 30 the former in opposite direction to the hinged end of the latter, as shown in Fig. 2. A bow spring 59 having one leg fastened to the outer member of the pneumatic 58 and the other leg fastened to the movable member of the pneumatic 31 serves to normally hold the pneumatic in expanded position as shown. During playing of the note-sheet suction is constantly applied to the pneumatic 58 through the tube 56 and port 40 57, causing said pneumatic to remain in a state of collapse and permitting complete freedom of action of the movable member of the pneumatic 31. When, however, the suction ceases, as during re-rolling of the note-sheet, the spring 59 will immediately expand the pneumatic 58 against the U-shaped guard rail 60 and will move the movable member of the pneumatic 31 to the central or neutral position shown in Fig. 2, in which 45 position the note-sheet carrying roll 12 will be in its proper initial position relative to the tracker-bar. Regulating means 61 are preferably provided to permit of adjusting the central position of the movable member 50 of the pneumatic 31.

From the foregoing description the construction and mode of operation of my improved tracking device will be understood by those skilled in the art, and it will be apparent that various modifications may be 60 made therein without departing from the scope of my invention.

I am aware that prior to my invention automatic tracking mechanisms have been

devised in which a "guide-opening" is employed to control the operation of the mechanism, and accordingly I disclaim invention of the "guide-opening." I believe, however, that I am the first to improve such mechanisms by the provision of a bleed 65 which opens under the traveling note-sheet and which is self-cleaning by the suction or draft created upon re-rolling the sheet; and to provide a tracking device wherein all of the operative parts are mounted on a carriage, whereby transposition of the note-sheet may be effected without interfering with the operation of the device, as hereinabove described and as pointed out in the 70 claims.

What I claim is:

1. In combination a traveling note-sheet, a member having a pair of openings and a connecting groove disposed in the path of travel of an edge of the sheet, one of the 85 openings being partly, and the other opening and the groove being entirely, covered by said edge, and a pneumatic tracking device connected with said openings and governed by lateral displacements of the sheet 90 for automatically correcting such displacements.

2. In a musical instrument having air exhausting apparatus and employing a traveling note-sheet, the combination with 95 a pneumatically controlled tracking device and a guide-opening connected therewith for governing operation thereof, of an exhaust opening communicating with the air exhausting apparatus, and a groove connecting said openings and forming, when covered by the traveling sheet, a bleed between 100 said openings.

3. The combination of a perforated note-sheet, a fixed tracker having a notch in the path of travel of an edge of the sheet, a carriage adjustable longitudinally with respect to the tracker, means for adjusting the carriage, a note-sheet carrying roll and a take-up roll both carried by the carriage, 110 a plate mounted on the carriage to ride in the notch of the tracker, said plate having a pair of openings and a connecting groove over which an edge of the sheet travels, and pneumatic means communicating with said 115 openings and operative automatically to restore the sheet to its correct path of travel upon lateral displacement of the sheet.

4. The combination with a traveling note-sheet, air exhausting apparatus, and a 120 tracker having a guide-opening, of a groove in the face of the tracker and forming, when covered by the traveling sheet, a bleed between the guide-opening and the air exhausting apparatus.

5. In a pneumatic tracking device for a traveling note-sheet, a tracker provided with two openings and a connecting groove, said

groove forming a bleed between the openings when it is covered by the traveling sheet.

6. In a pneumatic tracking device of the character described, a note-sheet, a carrying roll and a take-up roll for said sheet, the carrying roll being movable endwise, a tracker having two openings and a connecting groove over which an edge of the sheet

travels, pneumatic means connected with said openings and operative upon lateral displacement of the sheet to shift the carrying roll in the opposite direction to an extent equal to the displacement, and pneumatic means for centralizing the position of the carrying roll during re-rolling of the sheet. 10 15

JOSEPH P. HULDER.
